UNITED STATES PATENT OFFICE.

WILLARD B. FEATHERSTONE, OF TOLEDO, OHIO, ASSIGNOR TO THE AUTOMATIC PRESSURE FEED LUBRICATOR COMPANY, OF LOS ANGELES, CALIFORNIA.

SYSTEM OF LUBRICATION.

No. 804,937.

Specification of Letters Patent.

Patented Nov. 21, 1905.

Application filed October 25, 1902. Serial No. 128,736.

To all whom it may concern:

Be it known that I, WILLARD B. FEATHERSTONE, a citizen of the United States, residing at Toledo, in the county of Lucas and State 5 of Ohio, have invented a new and useful Improvement in Systems of Lubrication, of which the following is a specification.

My invention relates to a system of lubrication by which lubricant is automatically supplied under pressure to the wearing parts of an engine or other mechanism; and the object 10 of my invention is to provide simple, inexpensive, and efficient means of utilizing elastic-fluid pressure, more particularly the varying pressure produced by pumps, explosive-engines, &c., for the purpose by automatically collecting and retaining in the lubricant-reservoir from such sources elastic fluid of sufficient density to exert an operative and substantial uniform pressure upon the lubricant and causing it to be evenly and forcibly delivered.

The object of my invention is accomplished as hereinafter described, and illustrated in the 25 drawings, in which—

Figure 1 is a front elevation of a lubricator which is provided with multiple outlets and adapted for the use of oil as a lubricant. Fig. 2 is a longitudinal vertical section through the pressure-conduit and the reservoir. Fig. 3 is a transverse vertical section on line X-X through the reservoir and the common feed-outlet therefrom. Fig. 4 is a transverse vertical section through the pressure reducing and relief conduit as constructed in a detached form and which may be connected to a source of pressure and to any lubricant-reservoir by suitable pipe connections. Fig. 5 is a transverse vertical section through an oil-cup 40 adapted to supply oil directly to the source of pressure.

In the drawings the reservoir 1 is preferably provided with glazed end closures 2, which are suitably secured in the ends of the 45 reservoir. The oil-outlet 3 extends from the bottom through the top of the reservoir and may be formed integral therewith and has a capacity to supply oil to one or more feed-pipes 4. Above the reservoir the outlet 3 is 50 provided with a valve-chamber 5, in the bottom of which a seat 6 is formed for a back-seating check-valve 7, which may be suitably loaded by means of a spring 8, which is in-

terposed between the top of the valve and a screw-plug 9, run in the top portion of the 55 chamber for adjusting the spring-pressure upon the valve, and the top of the valve-chamber is inclosed in a cap 10, tightly secured thereto by screw-threaded connections. From the valve-chamber 5 the outflowing oil is delivered through a port 10' into a nipple 11, having one of its ends connected to the port and the opposite end connected to a valve-casing 12. The valve-casing is provided with a nipple 13, having an outlet-port 14, which 65 is controlled by a suitable valve, preferably a needle-valve 15, which is mounted in the body of the casing. The valve-casing 12 may be provided with lateral side outlets 16, and by connecting a plurality of valve-casings by 70 means of nipples 17, as shown in Fig. 1, a distributing-manifold may be formed for any desired number of feed-pipes, each of which is separately controlled by a valve 15. The feed-outlet nipple 13 of each valve-casing is 75 exteriorly screw-threaded for attaching a sight-feed 18 to the valve-casing, or the feed-pipes 4 may be directly attached thereto by means of a union-coupling 19, as shown in Figs. 1 and 2.

The reservoir 1 is provided near one end with a standard 20, which also extends from the bottom to a little above the top of the reservoir, and within the body of the standard there is formed a pressure-duct 21, extending 85 through the standard and successively enlarged to form a valve-chamber 22 and a valve-chamber 23 above the chamber 22 and with the bottom of the chambers arranged to seat the valves 24 and 25, respectively, inserted 90 into said chambers.

From the valve-chamber 22 a conduit 26 is suitably extended to open into the upper part of the reservoir. Valve 25 is loaded by a spring 27, which is interposed between the 95 valve and plug 28, which is threaded into the top of chamber 23 and is formed with a cavity 29 to receive the spring. The plug is provided with a stem 31 of suitable length having a central longitudinal port 31' therethrough, and to the free end of the stem a wheel 32 is attached, or, if preferred, a removable key may be substituted for the wheel to run the plug into or out of the valve-chamber to compress the spring upon valve 25. The top of the 100 standard is exteriorly threaded to receive a 105

cap 33, which is provided with an aperture 34 to freely receive the projecting stem of the plug. To the lower end of the standard 20 a pipe 35 is suitably connected to convey to the reservoir compressed elastic fluid. The reservoir is also provided with a filling-aperture which is closed by means of a plug 36.

The diameter of duct 21 is preferably proportioned to reduce the pressure of the elastic fluid it transmits to about the degree of pressure desired in the reservoir. Such reduction of pressure, however, may be accomplished by a throttling-valve A, controlling the supply-pipe 35, as shown in Fig. 4, whereby a lubricator adapted for attachment to a source of low pressure may be adjusted for use when attached to a source of higher pressure. Such adjustment, however, is not necessary when exhaust-gas is utilized as a source of pressure and economy of pressure is unimportant.

Thus constructed and connected with a source of elastic fluid under pressure, whether variable or steady, the operation is as follows: The valve 25 being weighted to open at a definite lower pressure than the highest pressure in the source and the check-valve 24 being adapted to be opened by any pressure in excess of the pressure in the reservoir and to admit, through the duct 21, elastic fluid under pressure from the source into the valve-chamber 22, valve 25 will prevent the escape of any part of the elastic fluid through port 31' and direct it through the conduit 26 into the reservoir until the pressure therein slightly exceeds the resistance of the valve 25. The valve will then open and permit the escape of such excess through the port 31' to the outer air. If the pressure is steady in the source and exceeds the resistance of the valve 25, both valves will then remain open; but if the pressure in the source is variable or intermittent both will open and close with the variations of pressure above and below the pressure in the reservoir. In either case, however, a constant uniform pressure will be retained in the reservoir equal to the resistance of the valve 25. By adjusting the spring-pressure upon the valve 25 any predetermined degree of pressure may be maintained in the reservoir and exerted upon the oil to establish flow through the outlet 3 by raising the check-valve 7. Check-valve 7 is weighted or adjustably spring-pressed to prevent siphoning of the oil by gravity and is further adapted to prevent the return flow of oil which might be produced by back pressure in any of the feed-pipes 4. Any or all of the separate feed-pipes 4, but preferably those feed-pipes equipped with sight-feeds that supply oil to a portion of a mechanism liable to create an intermittent back pressure in the feed-pipes, may be each provided with a return check-valve 38, which is attached to the feed-pipes in a suitable position. To relieve the pressure in the reservoir and stop the feed of oil within a reasonable time after

lubrication becomes unnecessary, I have provided a minute aperture 39, which is arranged to establish communication between the interior of the reservoir and the atmosphere. While the mechanism is in motion and requiring lubrication, the leakage thus produced is constantly supplied by an excess of compressed elastic fluid conducted to the reservoir. When at rest the leakage soon reduces the pressure in the reservoir below that required to open the check-valve 7, which then closes and stops the flow of oil.

By making the reservoir 1 of octagonal cross-section the general appearance of the lubricator is enhanced, and by arranging the sight-feeds of the outlets opposite to the inclined side 40 of the reservoir the same may be provided with a reflector 41, adapted to bring into prominent relief drops of oil accumulating at a point 42 of the needle-valve, the point of which is of a length to be visible through the glazed sight-openings 43 of the sight-feeds.

In the modification shown in Fig. 4 I have provided a separate casing 44, in which the restricting-duct 21^a and the valve-chambers 22^a and 23^a are formed, and in the top of the chamber 23^a is threaded a pierced plug 45 to adjust the compression of the spring 27^a, which is inserted into the chamber between the top of the valve 25^a and the plug 45. The pressure-duct 26^a is arranged in the form of a port to which a conduit 46 is connected and arranged to open into the top of the reservoir. The plug 45 is provided with a leak-port 31^a, and between the conduit 46 and the valve-chamber 23^a is provided a minute vent 39^a, and the casing 44 is connected to a source of pressure by a supply-pipe 35^a. In this modified form of my invention the several parts designated in the drawings by numerals having the sign "a" added thereto have like functions as parts designated by the same numerals without the sign "a" in Figs. 1, 2, and 3, and the operation is substantially the same as hereinbefore described.

In the modification illustrated in Fig. 5 there is shown an embodiment of my invention in a single-feed lubricator 47, in which the central standard 48 is provided with the outlet-chamber 5^b, arranged under the valve-chamber 22^b and separated therefrom by means of a plug 49, which is also adapted to adjustably compress the loading-spring 8^b upon the check-valve 7^b. The pressure-inlet duct 21^b is arranged to one side in the body of the standard and communicates with the inlet 50 to valve-chamber 22^b by an intersecting lateral duct 51, which is formed above the plug 49. The other parts, comprising the chamber 23^b, the valves 24^b and 25^b, the conduit 26^b, the spring 27^b, the plug 28^b, having a cavity 29^b and a stem 31^b, provided with a leak-port 31^b, and the cap 33^b, are substantially the same in construction, relation, and function

as hereinbefore described for the parts designated in Figs. 1, 2, and 3 by the same numerals without the sign "b" attached. From the valve-chamber 5^b a duct 52 is extended to intersect with the outlet-port 53, which delivers oil into the body of a reducer-coupling 54, suitably attached to the bottom of the lubricator 47 and adapted to couple it to the cylinder or any other part of an air-pump, explosive-engine, or other mechanism which in its operation requires lubrication and is adapted to serve as a source of pulsating or variably-compressed elastic fluid. This form of lubricator, as is apparent, is only operative when attached to such source of pressure, as when attached to a source of uniform pressure the back pressure on the outlet of the oil-feed duct is constantly greater than the reduced pressure admitted into the reservoir. It is manifest, however, that by reason of the rapid alternation of high and low pressure in the source the uniform mean pressure maintained in the reservoir will produce a substantially constant oil-feed. It is obvious also that the construction and operation of this form of lubricator does not differ in principle from that of the other forms shown and described and that it differs from them only in combining the several pressure and oil ducts and their controlling-valves in one common standard within the reservoir and in its more limited application, its operation being in all other respects as described.

It is further obvious that when a lubricator of either of the forms shown in Figs. 1 and 4 is attached to a source of elastic fluid under uniform pressure the check-valve 24 is not necessary to its operation; but by its use such lubricator is made available for use with either steady or variable pressure without change or modification.

What I claim to be new is—

1. In a lubricating system for supplying lubricant under pressure, a reservoir for the lubricant having one or more feed-outlets, a conduit adapted to be connected with a source of elastic fluid under pressure, and having an open port to the atmosphere, a connection from the conduit to the reservoir between the port and the source, a back check-valve in the conduit between the connection and the source, and an adjustably-weighted relief-valve in the conduit between the connection and the port, adapted to limit the exit of elastic fluid from the port.

2. In a lubricating system for supplying lubricant under pressure, a reservoir for the lubricant having one or more feed-outlets, a conduit adapted to be connected with a source of elastic fluid under pressure, and having an open port to the atmosphere, a connection from the conduit to the reservoir between the port and the source, a back check-valve in the conduit between the connection and the source, an adjustably-weighted relief-valve in the con-

duit between the connection and the port, adapted to limit the exit of elastic fluid from the port, and a time-vent from the reservoir to the outer air.

3. In a lubricator system for supplying lubricant under pressure, a reservoir for the lubricant, having one or more feed-outlets, a conduit adapted to be connected with a source of elastic fluid under pressure, an inlet-chamber having a port connected to the conduit and a connection to the reservoir, a back check-valve in the inlet-chamber controlling the port to the conduit, an outlet-chamber having a port connected to the inlet-chamber and an opening to the atmosphere, a relief-valve in the outlet-chamber adapted to normally close the port from the inlet-chamber to the outlet-chamber, and means to adjustably weight the valve in the outlet-chamber. 70

4. In a lubricating system, a reservoir for the lubricant having a distributing-chamber provided with one or more valve-controlled feed-outlets, an oil-conduit connecting the reservoir with the distributing-chamber, a back check-valve controlling the oil-conduit, a gas-conduit adapted to be connected with a source of elastic fluid under pressure, an inlet-chamber having a port connected to the gas-conduit and a connection to the reservoir, a back check-valve in the inlet-chamber controlling the port to the gas-conduit, an outlet-chamber having a port connected to the inlet-chamber and an opening to the atmosphere, and a relief-valve in the outlet-chamber adapted to normally close the port from the inlet to the outlet chamber, and means to adjustably weight the valve in the outlet-chamber. 85

5. In a lubricating system, a reservoir for the lubricant having a column extended therein and projecting above the reservoir, a valve-chamber in the projection and an oil-duct in the column connecting the valve-chamber with the reservoir, a back check-valve in the chamber adapted to control the oil-duct in the column, means to adjustably weight the check-valve, a manifold ported to the valve-chamber and having a plurality of valve-controlled feed-pipes, a gas-conduit adapted to be connected with a source of elastic fluid under pressure, an inlet-chamber having a port connected to the conduit and a connection to the reservoir, a back check-valve in the inlet-chamber controlling the port to the gas-conduit, an outlet-chamber having a port connected to the inlet-chamber and an opening to the atmosphere, and a back-pressure valve in the outlet-chamber adapted to close the port from the inlet-chamber, and means to adjustably weight the valve in the outlet-chamber. 95
